Primary Examiner — Cynthia Ramirez*Assistant Examiner* — Michael A Maharajh(74) *Attorney, Agent, or Firm* — Morgan, Lewis & Bockius LLP(57) **CLAIM**

The ornamental design for an exercise apparatus, as shown and described.

DESCRIPTION

FIG. 1 is a perspective view of an exercise apparatus showing our new design;

FIG. 2 is a front view, the back view is a mirror image thereof;

FIG. 3 is a top view thereof;

FIG. 4 is a bottom view thereof; and,

FIG. 5 is a side view, the opposite side is a mirror image thereof.

The band is shown with a symbolic break in its length. The appearance of any portion of the article beyond the break lines forms no part of the claimed design.

The broken lines shown in the figures are for the purposes of illustrating portions of the exercise apparatus which form no part of the claimed design.
